United States Patent Office.

JAMES CARLISLE, OF MOUNT GILEAD, OHIO.

Letters Patent No. 68,486, dated September 3, 1867.

IMPROVED RAIL FOR BUGGY-SEAT.

The Schedule referred to in these Letters Patent and making part of the same.

TO ALL WHOM IT MAY CONCERN:

Be it known that I, JAMES CARLISLE, of Mount Gilead, in the county of Morrow, and State of Ohio, have invented a new and useful improvement in Adjustable Rails for Buggy-Seats; and I do hereby declare that the following is a full, clear, and exact description thereof, which will enable others skilled in the art to make and use the same, reference being had to the accompanying drawings, forming part of this specification.

The present invention relates to a shifting-rail, or, in other words, to the adjustment of the top to the seat, and, in the arrangement and construction of parts embraced in the present invention. The top rail is adjusted to the seat by its own spring, and there held by the fastenings with which it is provided. In the accompanying plate of drawings my improvement in adjustable rails for buggy-seats is illustrated—

Figure 1 being a plan or top view of the seat proper, and

Figure 2 a cross vertical section of the rail carrying the top.

Similar letters of reference indicate like parts.

A in the drawings represents a buggy or other carriage-seat, around the upper edge B of which is fixed a metal band or rail, C, to project over such edge upon the outside of the seat. This band C is secured by screws or other suitable fastening devices, and at the front of the seat is continued down in a curved or bent shape for forming arms D thereto. E, the rail which is to carry the buggy top, and F the lazy-back thereto. This rail, by its hooks a at the outer end of the side pieces G, is interlocked with the notches b in the bearing-bar C of the seat, and by its notches c over the back edge of the said bar, with its pins d inserted in the eyes e at and along the sides to the seat.

When the rail E is to be adjusted it is first set by its hooks a into the notches b upon the front of the seat, and by its pins d into the eyes e, when, springing the back over the back edge, its notches there interlocking with the projecting edge of the bearing-bar, securing the rail firmly and rigidly in place without danger of rattling by the running of the carriage.

I claim as new, and desire to secure by Letters Patent—

The bearing-bar C to a buggy or other seat, in combination with the rail E, when both are constructed so that the one will fasten to and upon the other, substantially as and for the purpose described.
